US00D908018S

(12) **United States Design Patent** (10) **Patent No.:** **US D908,018 S**
(45) **Date of Patent:** **** Jan. 19, 2021**

(54) **PACKAGING WITH ACCESSORY**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Jeremy Bataillou**, San Francisco, CA (US); **Daniel J. Coster**, San Francisco, CA (US); **Danielle De Iuliis**, San Francisco, CA (US); **M. Evans**, **Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/747,618**

(22) Filed: **Aug. 24, 2020**

Related U.S. Application Data

(63) Continuation of application No. 29/706,723, filed on Sep. 23, 2019, now Pat. No. Des. 894,017, which is (Continued)

(51) **LOC (13) Cl.** **09-01**

(57) **CLAIM**

The ornamental design for packaging with accessory, as shown and described.

DESCRIPTION

FIG. 1 is a perspective view of packaging with accessory showing the claimed design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines in the figures show portions of the packaging with accessory that form no part of the claimed design.

1 Claim, 5 Drawing Sheets

Related U.S. Application Data

a continuation of application No. 29/629,980, filed on Dec. 18, 2017, now Pat. No. Des. 860,810, which is a continuation of application No. 29/598,220, filed on Mar. 23, 2017, now Pat. No. Des. 807,761, which is a continuation of application No. 29/546,675, filed on Nov. 24, 2015, now Pat. No. Des. 782,327, which is a continuation of application No. 29/489,065, filed on Apr. 25, 2014, now Pat. No. Des. 744,855, which is a continuation of application No. 29/431,882, filed on Sep. 12, 2012, now Pat. No. Des. 704,072.
